UNITED STATES PATENT OFFICE.

IRA J. GRIFFIN, OF SING SING, NEW YORK.

NUT-LOCK.

SPECIFICATION forming part of Letters Patent No. 443,675, dated December 30, 1890.

Application filed March 25, 1890. Serial No. 345,209. (No model.)

To all whom it may concern:

Be it known that I, IRA J. GRIFFIN, of Sing Sing, in the county of Westchester and State of New York, have invented a certain new and useful Improvement in Nut-Locks, of which the following is a specification.

The object is to provide means for effectually locking a nut against displacement, no matter how great the jar or in what direction the strain tending to release the nut may be exerted, and at the same time to provide for the ready removal of the locking device for the purpose of intentionally removing the nut.

With these ends in view my invention comprises a bolt having a longitudinal groove, a nut having one or more grooves or recesses, and a key adapted to enter the groove in the bolt and engage a recess in the nut.

My invention further comprises certain details of construction by means of which the key is securely locked in its position in engagement with the nut and in an auxiliary locking device adapted to use in connection with the key for further insuring the holding of the key in position either in connection with locking-teeth upon the key or independently thereof.

In the accompanying drawings, Figure 1 represents a bolt partly in section with nut and key in locked adjustment. Fig. 2 represents a nut, key, and portion of the bolt in side elevation with the releasing-wrench in position to remove the key. Fig. 3 represents a face view of the nut in detail. Fig. 4 represents a view of the key in side elevation. Fig. 5 represents a bottom plan view of the same; Fig. 6, a top plan view of the auxiliary locking attachment, and Fig. 7 a view of the lower portion of the releasing-wrench.

A represents a bolt provided throughout a portion of its length with screw-threads, as is usual. The bolt A has formed therein a groove *a*, extending from the end of its threaded portion toward the head a distance of half the length of the bolt, more or less.

B represents a nut having an internal thread, as is usual, and provided on its outer face or end with one or more grooves or recesses *b*. I prefer to locate the grooves or recesses *b* at frequent intervals along the margin of the bore of the nut and to extend them

radially from the bore of the nut to the outer edge of the nut, as shown clearly in Fig. 3. I further find it advisable to cut away the inner edge of the wall of the nut at the outer end of its bore, as shown at *b'*, for the reception of the shoulder of the key, as will hereinafter more fully appear.

The general shape of the key is that of a **U**-shaped head, one of the branches of the **U**-shaped head being turned substantially at right angles to the other branch and extending for a considerable distance in the plane of the head portion.

The branches of the **U**-shaped portion of the key are denoted by the letters *C* *c*, and the extended portion of the branch *c* is denoted by *c'*. The latter is slightly curved in a direction away from the opening between the branches of the **U**-shaped portion, and the branch *C* is extended beyond the branch *c*, so that when the key is placed with the ends of its branches toward the bottom of the groove in the bolt the end of the branch *C* and of the extension *c'* will first engage the bottom of the groove and hold the rest of the key away from the bottom, the curved extension *c'* projecting normally out beyond the periphery of the bolt. The key is formed of some suitable spring metal—steel, for example—and that portion of the branch *c* toward the face or outer end of the nut is of such width as to enter one of the grooves or recesses in the end of the nut. The key is further provided with a shoulder *c²*, projecting from the branch *c* in position to engage the recess at the margin of the portion of the nut at the same time that the portion *c* engages the recess at the end of the nut. It follows from the above that when the nut is screwed on to the bolt and the key slid along in the groove in the bolt, its extension *c'* passing under the threaded wall of the nut, the wall of the nut will press inwardly on the extension *c'* and force the key firmly against the bottom of the groove in the bolt, and when the key has been forced so far as to bring its branch *c* into engagement with one of the recesses on the end of the nut the nut will be held by the key against a rotary motion, while the key will be held by the nut against a longitudinal motion.

In order to prevent the key from any lia-

bility of sliding longitudinally in the groove in the bolt, I provide an auxiliary locking attachment E, having a concave face e, provided with screw-threads adapted to register 5 with the threads on the bolt. The front and rear walls of the piece E are recessed, as shown, at e' to receive the inner edges of the branches C c of the key, whereby the attachment E may be inserted and held between the 10 said branches of the key in position to engage the threads of the bolt. The back of the attachment E is beveled, as shown at e², Figs. 1 and 2, so that the said attachment is allowed a slight rocking motion toward and away from 15 the end of the nut between the branches of the key. From this construction it follows that any tendency of the key to slide outwardly from its locked position in engagement with the nut will tend to tilt the attachment 20 E and cause its threaded face to hug more closely the threads of the nut, and thereby effectually prevent any considerable sliding of the key. On the other hand, when it is desired to remove the key a wrench F, having 25 a bifurcated end, as shown, may be applied to the ends of the attachment E, and using the outer edge of the nut as a fulcrum the attachment may be slightly lifted and rocked into a position to release its threaded face 30 from the threads of the nut and at the same time release the end of the branch C of the key from the bottom of the groove, and thereby slide the key out of its position in engagement with the nut.

35 To still further insure the key against liability of displacement in cases where the item of a slight increase in cost does not enter as material, I provide the end of the branch C with one or more teeth g, adapted to interlock 40 with a series of notches or teeth G, formed along the bottom of the groove a of the bolt. These notches or teeth G may be made finer than the threads of the bolt, so as to form a lock for the key at very slight intervals.

45 What I claim as my invention, and desire to secure by Letters Patent, is—

1. The combination, with a bolt provided

with a longitudinal groove and a nut having one or more recesses on its outer end or face, 50 of a key having a U-shaped outer portion, the outer branch of the U-shaped portion projecting into and engaging at its end the bottom of the groove in the bolt, the inner branch of the U-shaped portion constructed to engage 55 the recess in the end of the nut and having an extension extending along the groove within the nut, the said inner branch being held away from the bottom of the groove by the said extension, and the key being forced toward the bottom of the groove by the engagement of the nut with said extension, substantially as set forth.

2. The combination, with a threaded bolt having a longitudinal groove and a nut having 60 one or more recesses in its end, of the two-branch key having an extension to engage the inner wall of the nut, and a locking device held between the branches of the key 65 in engagement with the thread of the bolt, 70 substantially as specified.

3. In combination, the bolt having a longitudinal groove, a nut having one or more recesses in its end, a two-branch key fitted to enter the groove beneath the nut and to engage the recess in the end of the nut, and a locking device constructed so as to have a 75 rocking movement between the branches of the key and an engagement with the threads of the bolt, substantially as set forth. 80

4. In combination, the bolt having a longitudinal groove provided with notches or teeth on its bottom, a nut having one or more recesses in its end, the two-branch key having 85 an engagement with the inner wall of the nut and with the end of the nut, one of the branches of the key interlocking with the teeth or notches at the base of the groove, and a locking device located between the branches of the key in engagement with the 90 threads of the bolt, substantially as set forth.

IRA J. GRIFFIN.
